(57) **CLAIM**

The ornamental design for a race track tossing game, as shown and described.

DESCRIPTION

FIG. 1 is a top plan view of a race track tossing game showing my new design;

FIG. 2 is a side elevation view, the opposite side being a mirror image thereof;

FIG. 3 is a side perspective view thereof; and,

FIG. 4 is a top plan view of another embodiment, with turn numbers.

The sides of the race track tossing game are flat and unornamented.

The bottom of the race track tossing game is flat and unornamented.

The broken lines indicate unclaimed portions and form no part of the claimed design. The claimed design is flat.
